INK FOUNTAIN FOR ROTARY INTAGLIO
PRESSESJoseph E. Meyer, Westerly, R. I., assignor to C. B.
Cottrell & Sons Company, Westerly, R. I., a
corporation of Delaware

Application December 3, 1941, Serial No. 421,433

15 Claims. (Cl. 101—157)

The object of my invention is to provide improvements in the construction, form and arrangement of the several elements of an enclosed ink fountain for rotary intaglio printing presses whereby the structure of the fountain is materially simplified and the operation of its parts facilitated.

My invention comprises a novel and simple wiping mechanism for the design cylinder, which wiping mechanism includes a fixed back frame, a carriage reciprocable thereon and a swinging doctor frame reciprocable with the carriage.

My invention also comprises means swinging the doctor frame for adjusting the contact pressure of the doctor blade on the design cylinder, means serving as a stop for the doctor frame in its adjusted position, and means for removably locking the doctor frame to the carriage in its adjusted position.

My invention also includes novel and simple means for adjusting the wiping mechanism for use with design cylinders of different diameters.

A practical embodiment of my invention is represented in the accompanying drawings, in which

Fig. I represents a detail view, partly in section, of the front or inking mechanism side of the fountain;

Fig. II represents a detail view, partly in section, looking toward the inner wall of the inker head;

Fig. III represents a detail view of the back or wiping mechanism side of the fountain;

Fig. IV represents a detail section taken in the plane of the line IV—IV of Fig. III;

Fig. V represents a detail section taken in the plane of the line V—V of Fig. III;

Fig. VI represents a detail section taken in the plane of the line VI—VI of Fig. I;

Fig. VII represents a detail section taken in the plane of the line VII—VII of Fig. III;

Fig. VIII represents a detail section taken in the plane of the line VIII—VIII of Fig. VII;

Fig. IX represents a detail section similar to Fig. VII, showing the free end of the doctor frame released from the carriage with which the doctor frame reciprocates;

Fig. X represents a detail plan view, partly in section, of the doctor carriage reciprocating mechanism;

Fig. XI represents a detail side elevation, partly in section, of the same;

Fig. XII represents an enlarged detail section taken in the plane of the line XII—XII of Fig. III;

Fig. XIII represents an enlarged detail plan view, partly in section, of the ink fountain;

Fig. XIV represents a detail vertical section taken in the plane of the line XIV—XIV of Fig. XIII;

Fig. XV represents an enlarged detail section like Fig. XII, showing the positions of the parts when a smaller design cylinder is employed;

Fig. XVI represents an enlarged detail plan view, partly in section, of the same; and

Fig. XVII represents an enlarged detail section taken in the plane of the line XVII—XVII of Fig. XVI.

In Figs. I to XIV inclusive the movable parts of the ink fountain are shown adjusted and arranged for use in connection with a larger design cylinder denoted by 1; while in Figs. XV, XVI and XVII the parts are shown as adjusted and arranged for use in connection with a smaller design cylinder denoted by 1*. The impression cylinder, shown in dot and dash outline, is denoted by 2. The design cylinder shaft 3 is rotatably mounted in bearings 4 carried by end frames 5 uprising from a holder base 6, the inner walls 20 of which end frames form the side walls for the ink fountain bowl. The design cylinder is arranged to be laterally removed through the front of the ink fountain by any well known or approved means, not shown herein.

The interior of the base 6 forms the lower portion of the fountain bowl. The opening 7 in the top of the base 6 is shown as provided with a suitable screen 8. Ink outlet passages 9 lead upwardly and outwardly from stumps 10 in the bottom of the fountain bowl to the interior of a manifold 11 secured to the front wall of the base 6. An outlet pipe 12 leads from the manifold 11 to any desired point.

The mechanism for supplying ink to the design cylinder comprises the following elements;

The hollow inker head includes an outer member 13, an inner member 14, and a nozzle member 15. This inker head slidably contacts the inner walls of the end frames 5 to form an ink seal 35 at these points for the fountain bowl.

The outer member 13 of the inker head is provided with inwardly directed top and bottom flanges 16 and 17. The bottom flange 17 projects under and contacts with the bottom of the inner member 14 of the inker head, said flange 50 having a port 18 therethrough which opens to the space between the outer and inner inker head members and also to the ink supply line, to be hereinafter described.

55 The nozzle member 15 is secured to the inner

face of the top flange 18 of the outer member for vertical adjustment, as, for instance, by providing bolts 19 which pass through vertically elongated slots 20 in the nozzle member into engagement with the said top flange 18. This adjustment predetermines the width of the discharge slot 21 which is formed between the inwardly and downwardly inclined portion of the bottom wall of the nozzle and the inwardly and downwardly inclined portion of the top wall of the inner member.

The bottom wall of the nozzle member 15 is provided with a depending lip 22 which overlaps and is spaced from an uprising lip 23 on the top wall of the inner member 14 of the inker head, to serve as a baffle for the ink passing through the discharge slot 21 of the nozzle.

Spaced lugs 24 project from the outer wall of the inner member into contact with the inner wall of the outer member, to provide a manifold comprising upper and lower horizontal passages 25 and 26 and their connecting vertical passages 27. The upper passage of the manifold opens to the ink discharge slot 21 and the lower passage 26 opens to the ink supply line through the port 18 in the bottom flange 17 of the outer member 13 of the ink head. Screws 28 serve to secure the inner and outer members of the inker head together.

The inker head is shown as hinged to the base 6 of the fountain to be swung between substantially vertical and horizontal positions, by providing the outer member 13 with lugs 29 pivoted to ears 30 uprising from the top of the base.

The inker head may be provided with a guard plate 31 which is secured to the outer member by the screws 32, 33.

Sealing means are provided for the ink fountain bowl where the inker head is hinged to the base, as follows:

An inner sealing plate 34 is secured to the outer member 13 by the screws 35. The beveled upper portion of this plate snugly overlaps the inner end of the lower flange 17 of the outer member and also the inner wall of the inner member 14 of the inker head. The lower portion of this sealing plate 34 is curved at the hinge connections between the inker head and base. A sealing plate spring 36 carried by a sealing plate 37 is secured by screws 38 to a rib 39 uprising from the top of the base 6. This spring 36 contacts the concave outer wall of the sealing plate 34 when the head is in its closed position.

The ink supply line includes a supply pipe 40 having a vertical extension 41 which carries the fixed outer member 42 of a swing pipe joint, the rotatable inner member 43 of which pipe joint is provided with an extension 44 secured to the bottom flange 17 of the outer member 13 of the inker head with the bore of the extension 44 in alignment with the port 18 through said bottom flange.

The axis of this swing pipe joint is in alignment with the axes of the hinge connections between the lugs 29 of the inker head and the ears 30 of the base, so that the inker head, when unlocked, may be freely swung to its open and closed positions without disturbing the connection between the ink supply pipe 40 and the interior of the inker head.

It will be understood that means, not shown herein, may be provided for receiving the ink from the bottom of the fountain bowl and forcing it into the inker head. Also, suitable means,

not shown herein, may be used for cutting off the ink supply before the inker head is swung to its open position.

Means are provided for locking the inker head in its closed or inking position, which means is shown herein as comprising two similar manually operated locking devices, one at each end of the head.

The inner wall of each of the end frames 5 has a properly positioned recess 45. A stud shaft 46 is rotatably mounted to turn in a sleeve 47 threaded into the outer member 13 of the inker head. The outer end of this stud shaft 46 is provided with a handle 48 for turning it. The inner end of this stud shaft is provided with an eccentric cam disc 49 arranged to be brought into and out of the recess 45 as the stud shaft is turned, to lock and unlock the inker head. This stud shaft 46 may be adjusted endwise for positioning the locking device for design cylinders of different sizes within predetermined limits. This adjustment is accomplished by the screw threaded engagement of the sleeve 47 with the outer member 13 of the inker head. A lock nut 51 on the sleeve 47 serves to lock the shaft 46 in its endwise adjusted position.

Devices, as swinging stops 52, are provided for limiting the inward movement of the inker head. Upper and lower pins 52* are provided for limiting the upward and downward movements of the stops 52; and upper and lower devices, as spring locks 52** are provided for yieldingly holding the stops 52 in their raised or lowered position.

The outer member 13 of the inker head may be provided with handles 53 for swinging the head to its open and closed positions. A cover plate 54 extends from one end frame to the other and this cover plate is hinged at 55 to the top of the inker head. An inwardly directed sealing strip 56 of suitable material is secured to the free end of the cover plate 54 in position to contact the surface of the design cylinder when the cover plate is swung to its closed position. An outwardly directed guard strip 57 is also secured to the free end of the cover plate 54.

This cover plate is provided with locking lugs 58 for engagement with sliding latches 59 on the end sealing devices to be immediately described, for locking the cover plate in its closed or inking position.

It will be seen that the inner walls of the sealing plate 34, the inner member 14, the nozzle member 15, and the cover plate 54 serve, when the inker head is closed, to form the front wall of the ink fountain bowl.

Means are employed for sealing the top of the fountain bowl beyond the ends of the design cylinder between the inking mechanism and the wiping mechanism, said means comprising two removable end sealing devices.

Each end sealing device is shown as comprising fixed and removable complementary plate members 60 and 61, the removable plate member 61 serving to fill in a cut-away portion in the fixed plate member 60. This fixed plate member 60 is shown as provided with a depending flange 62 having open ended slots 63 through which bolts 64 pass to removably secure the fixed plate member to its end frame 5.

These plate members 60 and 61 are curved and overlap the top side of the design cylinder at its end to the end of the impression cylinder 2. A flexible curved contact plate 65 is positioned to contact the top side of the design cylinder at its

end and this contact plate is secured, as by rivets 66, to the under side of the removable curved plate member 61. This flexible contact plate 65 with its imposed plate member 61 is shown as removably secured to the under side of the fixed plate member 60 by providing the contact plate with portions which underlap the fixed plate member and are there provided with open ended slots 67 which embrace pins 68 projecting from the under side of the fixed plate member.

The latches 59 heretofore referred to for engaging the lugs 58 to lock the cover plate 54 to each of the end sealing devices, are slidably mounted on the outer wall of the fixed plate member 60 of the end sealing device, by providing the plate member with screws 69 which pass through elongated slots 70 in the said sliding latches.

It will be understood that to remove the design cylinder through the side of the fountain the inker head is swung down to its horizontal position resting on the base 6 and the plate members 61 and their cylinder contact members 65 of the end sealing devices may also be removed, if necessary.

A back frame 71 is fixedly mounted on the top of the hollow base 6, and the inner wall of the back frame forms the back wall of the enclosed fountain bowl. The ends of this back frame snugly contact the inner walls of the end frames 5 to seal the fountain bowl at these points. This inner wall of the fixedly mounted back frame 71 extends upwardly and inwardly to a point adjacent the top of the design cylinder and from thence extends diagonally upward and downward to the top of the frame. The upper part of this upwardly and inwardly extended portion of the inner wall of the fixed frame is substantially concentric with and spaced a short distance from the design cylinder.

The wiping mechanism for the design cylinder includes the following elements:

A doctor blade 72 is clamped between the members 73, 74 of its holder, which holder is removably secured to the free upper end of a doctor frame 75, the lower end of which doctor frame is hinged to a carriage reciprocable on the back frame. This arrangement permits the doctor blade to be swung into and out of its wiping contact with the design cylinder.

The carriage is mounted to reciprocate on the back frame by the following elements:

A plurality of alined brackets 76 have base flanges 77 secured, as by bolts 78, to an upwardly and inwardly inclined portion 79 of the outer wall of the fixed back frame 71, which upwardly and inwardly inclined portion 79 is located between a vertical lower portion and an upwardly and outwardly inclined upper portion of the back frame. These brackets 76 are provided with downwardly projecting arms having alined bearings 80 for slidably receiving the lower horizontally disposed reciprocating rock shaft 81. These brackets are also provided with upwardly projecting arms having alined bearings 82 for slidably receiving an upper shaft or rod 83, which is, in the present instance, shown as divided into two alined members.

The doctor reciprocating carriage 84 is mounted on and reciprocates with the lower and upper shafts 81 and 83, by providing the carriage with downwardly projecting arms having alined heads 85 embracing the lower reciprocating rock shaft 81 and also with upwardly projecting arms having alined heads 86 which embrace the two mem-

bers of the upper reciprocating shaft 83 and are secured thereto by set screws 87.

The doctor frame 75 is hinged to the carriage 84 by providing the frame at its lower end with alined lugs 88 which are fixedly secured by bolts 89 to the free ends of arms 90 fixed to the lower reciprocating rock shaft 81 by set screws 91.

The means for reciprocating the carriage 84, the shafts 81 and 83, and the doctor frame 75 includes the following elements:

A horizontally disposed drive shaft 92 is operatively connected by gears 93, 94 to the lower end of a vertically disposed shaft 95 rotatably mounted in upper and lower housings 96, 97 secured to one of the end frames 5. The upper end of this vertical shaft 95 is provided with an eccentric 98 on which is mounted in a suitable housing 99 one end of a horizontally disposed connecting rod 100, the other end of which rod is pivoted to a lug 101 on the end of the carriage 84.

The means for removably locking the swinging doctor frame 75 in its adjusted position to the reciprocating carriage 84 includes the following elements:

A pair of hooks 102 are mounted to swing into and out of engagement with their respective members of the reciprocating shaft 83, each hook having a screw threaded shank 103 which projects upwardly through a pivoted mounting 104 on the doctor frame 75 into position to be engaged by a manually operated hand wheel 105 threaded on said shank. These hand wheels 105 may be turned in one direction to tighten the hooks on the shafts, to lock the doctor frame in its wiping position. If it be desired to release the free portion of the doctor frame from the carriage 84 the hand wheels 105 are turned in the opposite direction sufficiently to permit the hooks 102 to be swung out of engagement with the shaft 83, and allow the doctor frame to be swung back to an inoperative position. The shanks 103 of the hooks 102 have flattened portions engaged by a slotted plate 104* of the mounting 104 to prevent the hooks from turning when being longitudinally adjusted and swung into and out of their locking positions.

Means are provided for manually swinging the doctor frame 75 when its free portion is released from the reciprocating carriage 84, to serve the double function of adjusting the wiping contact pressure of the doctor blade 72 and also for swinging the doctor frame into and out of its operative position. This means comprises a manually operated hand wheel 106 fixed to a shaft 107 rotatably mounted in suitable bearings 108 in a bracket 109 depending from the reciprocating carriage 84. This shaft 107 is provided with a worm gear connection 110, 111 with the reciprocating rock shaft 81, the gear 111 being fixed to the said shaft.

Adjustable screws 112 are mounted in the doctor frame 75 in position to bear against the heads 86 on the arms of the reciprocating carriage 84 to serve as stops for limiting the inward movement of the doctor frame and thus maintain the adjustment of the doctor blade with respect to the design cylinder.

The fixed back frame 71 of the fountain is provided along its top with an upwardly and outwardly inclined seat 113 on which a sealing blade 114 and its holder 115 are movable toward and away from the design cylinder to adjust the point where the sealing blade 114 presses against the under side of the doctor blade 72.

Bolts 116 serve to lock the sealing blade holder 115 in its adjusted position.

A channel 117 is formed along the top of the sealing blade holder 115 to receive any ink which may possibly pass between the under side of the doctor blade 72 and the edge of its sealing blade 114, and to prevent the ink from passing over the top of the fixed back frame 71 and downwardly along its outer wall.

The doctor blade holder may be provided with suitable handles 118 for handling the holder and its doctor blade when the holder is released from the doctor frame 75.

In Figs. XV, XVI, and XVII the parts of the fountain are shown adjusted for use in connection with a smaller design cylinder 1*. In this arrangement the end sealing devices for the larger design cylinder 1 are replaced by end sealing devices adapted for use with the smaller design cylinder. These devices comprise the fixed curved plate member 60*, the removable curved plate member 61* and the flexible contact plate 65*. This fixed curved plate member 60* is provided with an outwardly projecting flange 62* having open slots 63* for receiving the bolts 64. Also, the eccentric cam discs 49 of the locking devices are caused to engage the curved recesses 45* in the end frames 5 when the inker head is swung inwardly to a new position to bring its discharge slot 21 close to the periphery of the smaller design cylinder. Also, the stops 52 may be swung downwardly against the lower pins 52* and there yieldingly held by the lower spring locks 52**. The locking lugs 58 in this instance are engaged by the latches 59* on the end sealing member 60*.

When this smaller design cylinder is used the doctor frame 75 is swung inwardly to its adjusted position with its doctor blade 72 in wiping contact with the cylinder, the sealing blade holder 115 being first adjusted downwardly and inwardly to move it out of the way of the doctor frame and to properly position its sealing blade 114 for coaction with the doctor blade 72.

While I have shown only two sizes of design cylinders, it is obvious that the several parts hereinbefore mentioned may be adjusted or replaced for use with design cylinders of varying sizes.

From the above description it will be seen that the fixed back frame forms the back wall of the fountain bowl up to a point adjacent the doctor blade.

It will also be seen that by mounting the reciprocating carriage of the doctor frame on the fixed back frame and by hinging the doctor frame to the carriage the wiping mechanism and its adjusting elements are materially simplified.

It will also be seen that by the construction herein set forth the several movable elements of the wiping mechanism may be very simply and readily adjusted for design cylinders of different sizes.

The inking mechanism and end sealing devices shown and described but not claimed herein, form the subject matter of my copending application filed of even date herewith, its Serial Number being 421,432.

It is evident that various changes may be resorted to in the construction, form and arrangement of the several parts without departing from the spirit and scope of my invention, and hence I do not intend to be limited to the particular em-

bodiment herein shown and described, but what I claim is:

1. In an enclosed ink fountain for a design cylinder, a base, a back frame secured thereto, a carriage reciprocable on the back frame, a doctor frame hinged to the carriage, means for swinging the doctor frame to its wiping position, and longitudinally adjustable hooks mounted to swing on the doctor frame to engage the carriage, for removably locking the doctor frame to the carriage in its wiping position.
2. In an enclosed ink fountain for a design cylinder, a base, a back frame secured thereto, a carriage reciprocable on the back frame, a doctor frame hinged to the carriage, means for swinging the doctor frame to its wiping position, longitudinally adjustable hooks mounted to swing on the doctor frame to engage the carriage, for removably locking the doctor frame to the carriage in its wiping position, and means outside the doctor frame for operating the hooks.
3. In an enclosed ink fountain for a design cylinder, a base, a back frame secured thereto, a carriage reciprocable on the back frame, a doctor frame hinged to the carriage, means for swinging the doctor frame to its wiping position, longitudinally adjustable hooks mounted to swing on the doctor frame to engage the carriage, for removably locking the doctor frame to the carriage in its wiping position, and a device on the doctor frame for preventing the hooks from turning.
4. In an enclosed ink fountain for a design cylinder, a base, a back frame secured thereto, a carriage reciprocable on the back frame, a doctor frame hinged to the carriage, means for swinging the doctor frame to its wiping position, longitudinally adjustable hooks mounted to swing on the doctor frame to engage the carriage, for removably locking the doctor frame to the carriage in its wiping position, means outside the doctor frame for operating the hooks, and a device on the doctor frame for preventing the hooks from turning.
5. In an enclosed ink fountain for a design cylinder, a base, a back frame secured thereto, a carriage provided with upper and lower shafts slidably mounted on the back frame, a doctor frame fixed to the lower shaft, and means for rocking the lower shaft and thereby swinging the doctor frame to its wiping position.
6. In an enclosed ink fountain for a design cylinder, a base, a back frame secured thereto, a carriage provided with upper and lower shafts slidably mounted on the back frame, a doctor frame fixed to the lower shaft, means for rocking the lower shaft and thereby swinging the doctor frame to its wiping position, and means on the doctor frame for removably locking it to the upper shaft of the carriage in its wiping position.
7. In an enclosed ink fountain for a design cylinder, a base, a back frame secured thereto, a carriage provided with a lower shaft and two aligned members of an upper shaft slidably mounted on the back frame, a doctor frame fixed to the lower shaft, means for rocking the lower shaft and thereby swinging the doctor frame to its wiping position, and longitudinally adjustable hooks mounted to swing on the doctor frame to engage the members of the upper shaft, for removably locking the doctor frame to the carriage in its wiping position.
8. In an enclosed ink fountain for a design cylinder, a base, a back frame secured thereto, a carriage provided with a lower shaft and two aligned members of an upper shaft slidably mounted on the back frame, a doctor frame fixed

to the lower shaft, a hand wheel mounted on the carriage and having a geared connection with the lower shaft for rocking it and thereby swinging the doctor frame to its different wiping positions.

9. In an enclosed ink fountain for a design cylinder, a base, a back frame secured thereto, a carriage provided with a lower shaft and two aligned members of an upper shaft slidably mounted on the back frame, a doctor frame fixed to the lower shaft, a hand wheel mounted on the carriage and having a geared connection with the lower shaft for rocking it and thereby swinging the doctor frame to its different wiping positions, and longitudinally adjustable hooks mounted to swing on the doctor frame to engage the members of the upper shaft, for removably locking the doctor frame to the carriage in its wiping positions.

10. In an enclosed ink fountain for a design cylinder, a base, a back frame secured thereto, brackets on the back frame provided with aligned bearings, upper and lower shafts reciprocable in said bearings, a carriage provided with upper and lower heads embracing their respective shafts to reciprocate therewith, arms fixed to the lower shaft, a doctor frame secured to said arms, and means movable with the carriage for rocking the lower shaft to swing the doctor frame to its wiping position.

11. In an enclosed ink fountain for a design cylinder, a base, a back frame secured thereto, brackets on the back frame provided with aligned bearings, upper and lower shafts reciprocable in said bearings, a carriage provided with upper and lower heads embracing their respective shafts to reciprocate therewith, arms fixed to the lower shaft, a doctor frame secured to said arms, and means movable with the carriage for rocking the lower shaft to swing the doctor frame to its wiping position, said means including a hand shaft geared to the lower reciprocating shaft.

12. In an enclosed ink fountain for a design cylinder, a base, a back frame secured thereto, brackets on the back frame provided with up-

wardly and downwardly projecting arms having aligned bearings, upper and lower shafts reciprocable in said bearings, a carriage provided with upper and lower arms having heads embracing their respective shafts to reciprocate therewith, arms fixed to the lower shaft, a doctor frame having lugs secured to said last named arms, and means movable with the carriage for rocking the lower shaft to swing the doctor frame to its wiping position.

13. In an enclosed ink fountain for a design cylinder, a base, a back frame secured thereto and extending upwardly and inwardly to a point near the top of the design cylinder, a carriage reciprocable on the back frame, a doctor frame hinged to the carriage, a doctor blade, a sealing blade, and a holder therefor, mounted on the back frame and having a channel along its upper wall for receiving any ink which might pass between the doctor and sealing blades.

14. In an enclosed ink fountain for a design cylinder, a base, a back frame secured thereto, a carriage reciprocable on the back frame, a doctor frame hinged to the carriage, means for swinging the doctor frame to its wiping position, screws carried by the doctor frame and engaging the carriage to stop the doctor frame in its wiping position, and longitudinally adjustable swinging hooks carried by the doctor frame and engaging the carriage for locking the doctor frame in its wiping position.

15. In an enclosed ink fountain for a design cylinder, a base, a back frame secured thereto, a carriage reciprocable on the back frame, a doctor frame hinged to the carriage, means for swinging the doctor frame to its wiping position, longitudinally adjustable hooks mounted to swing on the doctor frame for removably locking it to the carriage, and a slotted plate on the doctor frame, said hooks having flattened shanks slidably engaging the plate for preventing the hooks from turning, said hooks also being operable from outside the doctor frame.

JOSEPH E. MEYER.
